UNITED STATES PATENT OFFICE.

JAMES H. LA MENT, OF EAST TROY, PENNSYLVANIA.

DESIGN FOR A LAMP-CHIMNEY.

SPECIFICATION forming part of Design No. 21,558, dated May 24, 1892.

Application filed March 18, 1892. Serial No. 425,479. Term of patent 14 years.

To all whom it may concern:

Be it known that I, JAMES H. LA MENT, a citizen of the United States, residing at East Troy, in the county of Bradford and State of Pennsylvania, have invented and produced a new and original Design for Lamp-Globes; and I do declare the following to be a full, clear, and exact description of the same, reference being had to the accompanying drawings, forming a part thereof, in which--

Figure 1 is a front elevation of the globe; and Fig. 2, a section on line 2 2, Fig. 1.

The design consists, essentially, of a lamp-chimney having its body or bulbous section flattened on two opposite sides, so that a flat round surface is presented on each side of the lamp-chimney.

A represents the chimney; A', the bulbous section, and B B' the two flattened surfaces, each of which forms a circular panel on each side of the bulbous section A'. These flat surfaces B B' are divided up into smaller panels *a* and *b*, respectively, the latter of which is provided with scalloped ends *c*.

What I claim is--

The design for a lamp-chimney, as herein described and shown.

In testimony whereof I affix my signature in presence of two witnesses.

JAMES H. LA MENT.
